Patented Jan. 10, 1922.

UNITED STATES PATENT OFFICE.

ROY C. HUSE AND LELAND V. GORDON, OF KINGFIELD, MAINE.

RAZOR STROP.

1,403,324.

Specification of Letters Patent. Patented Jan. 10, 1922.

Application filed July 28, 1919. Serial No. 313,851.

To all whom it may concern:

Be it known that we, Roy C. Huse and Leland V. Gordon, citizens of the United States, residing at Kingfield, in the county of Franklin and State of Maine, have invented new and useful Improvements in Razor Strrops, of which the following is a specification.

This invention relates to razor strop attachments and the primary object of the same is to provide a simple and effective razor strop sterilizing means embodying special features hereinafter specified whereby a strop may be readily withdrawn from the attachment for use and subsequently quickly replaced within and enclosed by the attachment, the operation of returning the strop within the attachment being, in some instances, automatic and depending upon the position of the parts or the particular manner of applying the same to a holding means or support. With these and other objects and advantages in view, the invention consists in the preferred construction and arrangement of the several parts which will be more fully hereinafter described and claimed.

In the drawing a preferred embodiment of the improved sterilizing attachment or device is illustrated and capable of such modifications as fairly fall within the scope of the appended claims, and in the drawing:

Figure 1 is a prespective view of the improved attachment showing the razor strop withdrawn and broken away.

Figure 2 is a longitudinal vertical section of a portion of the outlet extremity of the attachment and of the razor strop in full and dotted lines showing the swivel movement of the strop.

Figure 3 is a horizontal section taken through the attachment and broken away, and illustrating the strop enclosed or inserted in the main body or enclosure of the attachment.

Figure 4 is a longitudinal vertical section of the attachment broken away in part and showing the strop fully inserted in the enclosure or main body of the attachment.

Figure 5 is a transverse vertical section taken in the plane of the line 5—5, Figure 3.

Figure 6 is a transverse vertical section taken in the plane of the line 6—6, Figure 3.

The improved attachment or sterilizing device comprises a tubular body or enclosure

5 of suitable dimensions and preferably formed from copper, brass or other sheet metal, nickel plated or otherwise ornamented. In one one end of the tubular body 6 or enclosure 5 is a cup or container 6 for a sterilizing pad 7 suitably mounted and held therein, the cup or container 6 being provided with a handle or grip 8 on its outer closed end for convenience in withdrawing and inserting the same from and into the one end of the body or enclosure 5, said cup or container being held in the body or enclosure against accidental displacement by interlocking indentations 9 and 10, respectively, formed in the body and one side of the cup or container. The inner end of the cup or container 6 is fully open and exposed to the interior of the body or enclosure 5, the said cup container being formed of the same metal or material as the body or container. At the opposite end of the body or container 5 is a partial closure 11 also formed of the same metal or material as the body or container and provided with an inwardly projecting surrounding annular guard flange 12 which slopes or is inclined towards the center of the interior of the body or enclosure 5.

The opening 13 defined by the flange 12 is large enough to permit a razor strop 14 to move outwardly and inwardly therethrough, but as will be hereinafter explained, said flange serves as a check for part of the attachment. Extending across the body or enclosure 5 are stop bolts 15 which are enclosed by sleeves 16 within the body, these bolts and sleeves serving as a stop means for

a slide 17 freely movable within the body or enclosure 5 and having a front tapered or reduced extremity 18 through the center of which the clip 19 of the razor strop is connected by a swivel bolt or rod 20 having an eye 21 movably mounted in a slot 22 in the front reduced extremity of the slide 17 and held by a cross pin 23, the outer or opposite end of the bolt or rod 20

being provided with a swivel head 24 to fit within a rear curved slotted extremity 25 of the razor strop clip 19, the bolt or rod 20 being free to move or shift within the clip so as to permit the razor strop 14 to be turned in various positions for use when withdrawn from the body or enclosure 5.

The slide 17 may be formed of wood or metal and will serve as a weight connection as well as a slide for assisting in returning

the razor strop 14 within the body or enclosure 5 after the strop has been used. When the strop 14 has been fully returned or inserted within the body or enclosure 5, the slide 17 will bear against the stop means provided by the bolts 15 and sleeves 16, the said stop means being in advance of the forward terminal of the cup or container 6 and thereby permit the latter to be clear and unengaged at any time by the slide. By reason of the stop means also the inner fully open end of the cup or container 6 will be prevented from being closed so that the sterilizing material or substance carried by the pad 7 will be free to act or circulate within the interior of the body or container 5 and properly affect or sterilize the razor strop. Any suitable sterilizing substance or material may be applied to the pad 7, but it has been found that formaldehyde is very effective for the purpose, and the sterilizing substance may be replenished from time to time by removing or withdrawing the cup or container 6 and afterwards resetting the same in the end of the body or enclosure 5. The improved attachment may be disposed in any position and secured to any suitable supporting or holding means. As shown, the body or enclosure 5 is arranged in horizontal position and securing angle brackets 26 are applied to opposite extremities by fastening devices 27, those of the forward angle bracket extending only through one side of the body or enclosure 5 to avoid obstructing the outlet of said body enclosure and the bolts 15 are utilized as the fastening means for the rear bracket 26. When the body or enclosure 5 is arranged in horizontal position the slide 17 is drawn outwardly through the casing by pulling on the strop 14, and conversely the said slide and strop can be moved into the casing by pushing on the strop, the latter having body enough to effect this insertion operation. It will also be noted that the body or enclosure 5 is rather narrow or is substantially rectangular in cross sectional contour and the slide is of the same contour but slightly smaller in dimensions so as to freely slide in the said body or enclosure. This configuration of the body and enclosure and the slide prevents the said slide from turning in the body or enclosure and the strop from twisting, yet there is ample space for the ready operation of the slide and strop. If desired, these brackets may be applied to one end of the body or enclosure 5 and disposed in planes at right angles to those shown by Figure 1, and in this event, the razor strop and the slide 17 would have a gravitating action when the strop was released after use and by properly turning the clip 19 to enter the outlet or pass through the opening 13 of the flange 12. Another advantageous feature of the improved structure is that the slide 17 always

holds the swivel coupling bolt or rod 20 in central position when the strop is drawn outwardly its full extent relatively to the opening 13, no matter in what position the body or enclosure 5 may be disposed. The slide 17 also reinforces the outlet portion of the body or enclosure 5 engaged thereby during the operation of the strop when the latter is withdrawn and turned in different positions, and, moreover, the slide is free to move, or has no restrictive devices connected thereto. The certainty of operation of the slide within the body or enclosure 5 is due to the fact that the said slide is of the same cross sectional shape as the body, but slightly less in dimensions relatively to the body. 70 75 80 85 90 95

From the foregoing operations of the improved attachment it will be readily understood that when the strop 14 is drawn out to its full length, the forward reduced extremity of the slide 17 engages the flange 12 and checks further outward movement of the strop, but the parts are so proportioned that when the slide does engage the flange the strop will be free for use, as shown in Figure 1, and may be turned at any angle owing to the swivel connection between the same and the slot. After the strop has been used, it may be turned and moved through the opening 13 of the flange 12 and either pushed inwardly or permitted to automatically withdraw or return to normal position in the body or enclosure 5. 95

The improved sterilizing attachment will be found exceptionally advantageous in the performance of the function for which it has been devised and will not only be effective in sterilizing a razor strop and maintaining the latter in proper condition for use, but will also protect the strop by the enclosure thereof from dust and dirt or flying particles in the air, and result in a hygienic preservation of the strop. 100 105 110

What is claimed is:—

1. In a device of the class specified, the combination of an enclosing tubular body open at one end, a slide mounted for free movement longitudinally in the body and of the same cross sectional contour as the latter, and a razor strop having a swivel connection to the center of the slide and movable through the open end of the body and freely turnable when disposed externally of the body, the body being adapted to be arranged either horizontally or at an angle to a horizontal plane, and the slide movable by the strop inwardly and outwardly with relation to the body, the strop being drawn inwardly into the body with the slide. 115 120 125

2. In a device of the class specified, a tubular body disposable both horizontally and at an angle to a horizontal plane, the one end of the body being fully open and the opposite end having a removable closure, 130

- a slide freely movable in and of the same cross sectional contour as the body, and a razor strop having a swivel connection to the center of the slide and movable through 5 the open end of the body, the slide being movable into the body solely by the strop when the body is in a horizontal plane, said slide also serving to maintain the swivel connection for the strop in central relation 10 to the outlet end of the body when the slide is moved to said outlet end.
3. In a device of the class specified, a tubular body having one end provided with a removable closing device, a slide of the 15 same cross sectional contour as the body and freely movable in the latter and unattached to any part thereof, the body being disposable in either a horizontal position or at an inclination relatively to a horizontal 20 plane, a razor strop having a swivel connection to the center of the slide and freely movable outwardly and inwardly through the open end of the body, the slide being moved into the body when the latter is in a 25 horizontal position solely by the strop, and means at the open end of the body for preventing the slide from passing out through said open end and becoming disengaged from the body.
- 30 4. In a device of the class specified, a tubular body having a removable closure in one end and the opposite end open, the open end of the body being provided with an interiorly projecting annular guard 35 flange, an unattached slide of the same cross sectional contour as the body and freely movable in the latter, and a razor strop having a swivel connection to the center of the slide and movable outwardly 40 and inwardly through the opening defined by the annular guard flange, the annular guard flange serving as a stop means to prevent the slide from moving outwardly through the open end of the body.
- 45 5. In a device of the class specified, a tubular body having means for applying the same in fixed position both horizontally and at an angle to a horizontal plane, the body having a removable closure in one end
- and the opposite end open, stop means extending across the interior of the body in advance of the said closure, a slide unattached to any part of the body or device within the latter in rear of the same, the slide having free unrestricted longitudinal 50 movement in the body and of the same cross sectional contour as said body, the slide engaging the stop means at its inward limit of movement to prevent contact thereof with the closure, and a razor strop 55 having a swivel connection to the center of the slide and freely movable through the open end of the body for use exteriorly of the latter and also operable to move the slide into and outwardly towards the outlet 60 of the body.
6. In a device of the class specified, a tubular body having one end open to serve as an outlet, a container removably mounted in and closing the opposite end of the body, 70 the body being disposable in a horizontal plane and also at an angle between horizontal and vertical planes, transversely extending stop devices in the body in advance of the container, a slide device of the same 75 cross sectional contour as the body and freely movable in and unattached to any part within the body in rear of said slide, the slide being freely movable longitudinally in the body to the open outlet end thereof, 80 but prevented from engaging the container by the stop devices, and a razor strop having a swivel connection to the center of the slide and freely movable through the open outlet end of the body, the strop being 85 utilized to draw the slide towards the outlet end of the body and also to push the slide rearwardly into the body when the latter is in a horizontal position.
- In testimony whereof we have hereunto 90 set our hands in presence of two subscribing witnesses.
